LAMP OR ANALOGOUS ARTICLE

Filed April 25, 1931

R. H. Rich, INVENTOR
BY Victor J. Evans
and Co. ATTORNEY

UNITED STATES PATENT OFFICE

ROBERT H. RICH, OF EAST HAMPTON, CONNECTICUT

DESIGN FOR A LAMP OR ANALOGOUS ARTICLE

Application filed April 25, 1931. Serial No. 39,621. Term of patent 7 years.

To all whom it may concern:

Be it known that I, ROBERT H. RICH, a citizen of the United States of America, residing at East Hampton, in the county of Middlesex and State of Connecticut, have invented a new, original, and ornamental Design for a Lamp or Analogous Article, of which the following is a specification, reference being had to the accompanying drawings, forming a part thereof.

Figure 1 is a perspective view, and Figure 2 is a plan view showing my new design.

I claim:—
The ornamental design for a lamp or analogous article.

ROBERT H. RICH.
